(57) **CLAIM**

The ornamental design for a bottle holder and accessory set, as shown and described.

DESCRIPTION

FIG. 1 is a top, front, right side perspective view of a bottle holder and accessory set showing my new design.

FIG. 2 is a top, rear, right side perspective view of my design shown in FIG. 1.

FIG. 3 is a front elevational view of my design shown in FIG. 1.

FIG. 4 is a right side elevational view of my design shown in FIG. 1.

FIG. 5 is a rear elevational view of my design shown in FIG. 1.

FIG. 6 is a left side elevational view of my design shown in FIG. 1.

FIG. 7 is a top plan view of my design shown in FIG. 1.

FIG. 8 is an exploded view of top, front, left side perspective view of my design shown in FIG. 1; and,

FIG. 9 is an exploded view of my design shown in FIG. 2. The bottom is flat and unornamented. The broken lines in FIGS. 8 and 9 are for the purpose of illustrating the relationship among the various parts and form no part of the claimed design.
